(57) **CLAIM**

We claim the ornamental design for a bicycle helmet, as shown and described.

DESCRIPTION

FIG. 1 is a perspective view of a bicycle helmet embodying the design.

FIG. 2 is a front elevation view of the design shown in FIG. 1.

FIG. 3 is a rear elevation view of the design shown in FIG. 1.

FIG. 4 is a left elevation view of the design shown in FIG. 1.

FIG. 5 is a right elevation view of the design shown in FIG. 1.

FIG. 6 is top plan view of the design shown in FIG. 1; and, FIG. 7 is a bottom plan view of the design shown in FIG. 1. The broken lines in the drawings illustrate portions of the bicycle helmet that form no part of the claimed design.

1 Claim, 7 Drawing Sheets
